UNITED STATES PATENT OFFICE.

ERNEST ROWLAND HILL, OF EAST ORANGE, NEW JERSEY.

AUTOMATIC TRAIN-CONTROLLING SYSTEM.

1,285,173.

Specification of Letters Patent. Patented Nov. 19, 1918.

Application filed December 19, 1914. Serial No. 878,005.

To all whom it may concern:

Be it known that I, ERNEST ROWLAND HILL, a citizen of the United States residing at East Orange, in the county of Essex 5 and State of New Jersey, have invented certain new and useful Improvements in Automatic Train-Controlling Systems, of which the following is a full, clear, and exact description.

10 The invention which forms the subject of the present application relates to so-called automatic train-control and "cab-signaling" systems, in which the travel of a train or vehicle is controlled or a signal displayed in 15 the cab, or both, through the agency of a device arranged alongside the track and co-operating with mechanism carried by the train. In a well-known system of this kind the track device has a ramp or incline in the 20 path of an upwardly movable device carried by the train, so that when the last-named device strikes the ramp it will be cammed upwardly. This upwardly movable device is connected with the air-brake system or other 25 appropriate mechanism, so that the actuation of the device by the ramp can stop the train or cause its speed to be reduced to a safe limit, and if desired actuate a signal in the cab. In the particular system referred 30 to, an electric circuit is usually provided on the train, and is so associated with the aforesaid device and the mechanism or apparatus actuated or controlled by it that if, at the same time that the device is moved upwardly by the ramp, current flows from the 35 ramp through said circuit the upward movement of the device will have no effect on the movement of the train. Accordingly the ramp is normally energized, so that current 40 can flow from it to the circuit mentioned, and is under the control of the signaling system used on the railway so as to be de-energized when conditions ahead (as for example the presence of a train in the next 45 block) require that the approaching train be stopped or have its speed reduced. In such case no current flows from the deenergized ramp, and the train device, actuated by the ramp, therefore has its full effect on 50 the movement of the train, through the agency of the air-brakes or other mechanism referred to. Or the apparatus may be arranged, not to control the travel of the train, but merely to cause a signal to be displayed 55 in the cab. In this case the flow of current

between the track device and the train device will cause the signal to show clear, and the actuation of the train device without such flow of current will cause the signal to show danger.

Another method of preventing any effect being produced by the ramp upon the movement of the train, except when required by conditions ahead, is to have the ramp normally out of the path of the train device but have it moved into the path of the device by the signal system whenever track conditions require.

In a system such as the one thus briefly outlined it is clear that the train device should be actuated only by the ramp. It is possible, however, for an obstruction along the track to actuate the train device and thereby occasion much inconvenience and delay if not actual damage; and I have therefore been led to devise my present invention, which has for its chief object to provide simple and effective means by which the path of the train device, in advance of the latter, will be kept clear of obstructions, without interfering with the function of the ramp. A further object is to provide for the above purpose means which will also serve to guide the ramp into the path of the train device, or to guide the train device into the plane of the ramp, thereby insuring actuation of the latter in spite of considerable lateral oscillation or motion of the vehicle or inaccurate placement of either device, and making it possible to use a train device and a ramp which are both comparatively narrow. To these and other ends the invention consists in the novel features of construction and combinations of elements hereinafter described.

A convenient and effective embodiment of the invention as applied to the system referred to above is illustrated in the accompanying drawing, in which—

Figure 1 is an end view and Fig. 2 is a side view, of a convenient and effective form of the invention.

Fig. 3 is a plan view showing a track-device of the type illustrated in Figs. 1 and 2, but combined with a signaling system whereby the device is normally energized and out of the path of the train device or the guards thereof, but is moved into such path and is deenergized when required by track conditions ahead.

Fig. 4 is a side view, on a smaller scale, of the preferred form of the track device, having an incline at each end.

In the construction illustrated the track device or "ramp" 10 is in the form of an elongated plate arranged in a vertical plane in substantial parallelism with the track (indicated by the rail 11) and its upper edge inclined at each end. The train device is a vertically movable plunger 12, the lower end of which is normally below the top of the ramp, so that when the plunger strikes either incline (according to the direction of travel) the plunger will be cammed upwardly and will produce the desired effect on the movement of the train. The means by which the action of the plunger produces the effect described is immaterial to the present invention and hence need not be illustrated or described herein. I have, however, shown diagrammatically at 12^a a part or member by which the plunger is carried, this part or member itself being carried by the vehicle (not shown) in any convenient manner. For example, it may be mounted on a yoke 13 having vertically slotted ends. This yoke is then clamped to the member 14 (which may be taken to represent any convenient part of the vehicle or a member carried thereby) by means of binding bolts 15. A considerable range of vertical adjustment is thus afforded. A face-plate 16 may be interposed between the member 14 and the yoke 13, and the coöperating faces of the face-plate and yoke can be roughened or grooved to eliminate any possibility of slipping after the desired adjustment has been made and the binding bolts tightened up.

For the purpose of keeping the horizontal path of the plunger 12 clear of obstructions, so that the plunger can be actuated only by the ramp, a guard 17 is provided in front of the plunger, formed with a downwardly open slot 18 to receive the ramp as indicated in Fig. 1, and extending below the plunger far enough to afford adequate protection to the same; it being understood that the plunger lies immediately in the rear of the slot.

To make the guard as effective as possible, the slot 18 therein is but little wider than the thickness of the ramp, a condition which would necessitate considerable accuracy in placing the ramp with respect to the plane of the plunger, and vice versa, and would allow of but little lateral motion or oscillation of the vehicle. To avoid this difficulty, the slot is made flaring (preferably at rather an acute angle) toward the front, as shown, thus providing two horns diverging toward the front, and the ramp is so mounted as to be capable of considerable lateral movement. Then if the ramp is anywhere inside the space spanned by the front ends of the horns 65 it will, when the guard meets it, be guided

into the plane of the plunger and will actuate the latter as desired. It is possible for small stones to become wedged in the slot, but being carried against the ramp with considerable velocity and being of small size 70 they are shattered by the impact or are carried clear through the slot into the open space between the guard and the plunger. Preferably the slot flares upwardly as well as forwardly so that a stone lodged between 75 the horns would readily be loosened and ejected by the upward camming action of the ramp.

The guard 17 can be mounted in position in any convenient manner, as by bolting it 80 to the underside of a shelf or bracket 19 at the bottom of the yoke 13.

The ramp 10 can be mounted in any suitable way to provide the desired lateral movement. For instance, in the arrangement 85 illustrated it is fixed on two transverse rods or supports 20 passing through the upright sides of two carriers 21 and adapted to slide therein. On one side of the ramp each rod is encircled by a sleeve 22, in which the rod 90 can slide, and between the heads 23 and the side of the carriers coil springs 24 are provided, serving to hold the ramp at about the center of the carriers, while the carriers themselves are so arranged (for example 95 mounted on the ends of the ties 25) as to give the ramp a position in or near the vertical plane in which the plunger 12 normally moves as it is carried forward by the vehicle. If the ramp is intended to carry current, insulators 26 can be interposed between the carriers 21 and the ties 25.

That the ramp may be energized under the control of the signaling system is indicated diagrammatically in Fig. 3, but it is 105 to be understood that the precise method used for the purpose is immaterial. In the arrangement illustrated, one terminal of a suitable source of current 27 is connected to the ramp and the other to ground through a 110 circuit-breaker 28 operated by the signaling apparatus 29. As long as the track ahead is clear the solenoid 30 holds the circuit-breaker in closed position and the ramp is "energized" or "alive," but if the signal 115 goes to danger or the signaling system is disabled the solenoid is deenergized, permitting the spring 31 to operate the circuit-breaker. The ramp is then "dead."

As stated above, the ramp can be normally out of the path of the plunger, and can be moved into such path by or under the control of the signaling system when danger conditions exist ahead of the train. For example, the carriers 21 can be mounted on 125 or connected to a pair of bell-cranks 32, fulcrumed on a base-plate 33 on the ties 25 and actuated by a rod 34 connected in any convenient manner with the signaling system, as by means of an air cylinder 35. When 130

the signal goes to danger or the apparatus is disabled, the compressed air escapes from behind the piston 36 (through a suitably controlled port not shown). The spring 37 then retracts the rod 34, thus rocking the bell-cranks clockwise and carrying the ramp 10 into the path of the train-device or into the space traversed by the horns of the guard.

It is to be understood that Fig. 3 is largely diagrammatic, its purpose being merely to indicate, in a general way, the relation of the track-device to the signaling system or other apparatus for the purpose. The skilled engineer or designer who undertakes to apply the invention in practice can readily supply all the necessary details and may even devise a method of control which would be better under the particular circumstances than that indicated.

By providing an incline at each end of the ramp or track-device 10, the controlling system will be operative for trains traveling in both directions, without employing two track-devices. If the same vehicle is to travel in both directions on the same track without being turned end-for-end the guard 17 can be removed and placed in rear of the plunger 12 before the vehicle starts back,

but a more convenient plan is to provide a rear guard 17^a, similar to the first but flaring in the opposite direction.

It is to be understood that the invention is not limited to the apparatus herein specifically illustrated and described, but can be embodied in other forms without departure from its spirit.

I claim:—

In an automatic train-controlling system, in combination, a movable controlling member adapted to be carried by a vehicle, a laterally movable track-device to actuate the controlling member, and a guard adapted to be carried by the vehicle in advance of the controlling member, having a downwardly and forwardly open slot flaring upwardly and toward the front to receive the laterally movable track-device and maintain the same in the path of the controlling member during the passage of the latter.

In testimony whereof I affix my signature in the presence of two subscribing witnesses.

ERNEST ROWLAND HILL.
